LIQUID COOLED BRAKE

John Hart Wilson, Wichita Falls, Tex.

Application September 14, 1938, Serial No. 229,940

8 Claims. (Cl. 188—264)

This invention relates to means for cooling heat-generating surfaces, and more particularly for cooling braking surfaces, by the use of a cooling liquid such as water, oil, or the like. Although liquids other than water may be used for cooling purposes, for the sake of convenience the liquid containing jackets hereinafter referred to will be called "water jackets" and water will be designated as the cooling liquid.

10 It is the general object of the present invention to provide a device of the character described, in which water jackets are provided at or near the heat-generating surfaces, and novel and advantageous means are provided for circulating water to and through the water jackets.

15 Another object is the provision of a device of the character described, including headers secured on a rotating shaft for rotation therewith, and conduits extending from said headers to and from the water jackets adjacent the heat-generating surfaces, whereby provision is made for circulating water to a plurality of water jackets.

20 A further object is the provision, in a device of the character described, of novel and advantageous means for introducing cooling water longitudinally through a rotating shaft, and withdrawing heated water therethrough, without substantial loss of heat from the outgoing heated water to the incoming cooling water.

25 Another object is the provision of a unit comprising an inlet conduit and an outlet conduit separated by heat insulating material, the said conduits being secured together to form a unitary assembly which may be bodily inserted in a suitable recess formed in the shaft of the rotating mechanism which includes the heat-generating surface or surfaces.

30 A further object is the provision of a unitary assembly such as described, in which the inlet and outlet conduits are semi-cylindrical in form, so that they may be welded or otherwise rigidly secured to form a cylindrical assembly which may be inserted bodily in a cylindrical recess in the shaft.

35 A further object is the provision of novel and advantageous means for introducing cooling water into the inlet conduit and withdrawing heated water from the outlet conduit.

40 Other and further objects, features and advantages of the present invention will be more apparent to one skilled in the art from the following description taken in connection with the accompanying drawings in which

45 Figure 1 is a longitudinal section through a

hoisting drum having braking surfaces, to which the present invention is applied;

Figure 2 is an enlarged detail view corresponding to the left hand end of Figure 1;

Figure 3 is a transverse section on line 3—3 of Figure 1;

Figure 4 is an enlarged detail view of the parts adjacent line 3—3 of Figure 1; and

Figure 5 is a fragmentary transverse section on line 5—5 of Figure 1.

10 In order to facilitate an understanding of the invention, reference is made to the embodiment thereof shown in the accompanying drawings and detailed descriptive language is employed. It will nevertheless be understood that no limitation of the invention is thereby intended and that various changes and alterations are contemplated such as would ordinarily occur to one skilled in the art to which the invention relates. Thus, while the present invention is illustrated and described as applied to a hoisting drum of the type commonly employed in connection with oil well machinery, it will be understood that the same or similar means may be employed for circulating water or other cooling liquid to heat-generating surfaces of many divergent natures, the present invention being suitable for application to most forms of rotating machinery having heat-generating surfaces such as braking surfaces.

20 Referring to Figure 1, the apparatus there illustrated comprises generally a shaft 10, supported for rotation in antifriction bearings 11 and carrying a drum 12 secured thereon. To the radial flanges 13, 13' of the drum 12 are secured annular flanges 14, 14', which comprise 25 braking surfaces adapted to be engaged by brake shoes 15, 15'. The mechanism for applying the braking pressure forms no part of the present invention and is not illustrated. The shaft 10 is adapted to be driven through a sprocket wheel 30 16.

35 Inwardly of each annular flange 14, 14' there is provided a water-tight jacket 17, 17', welded or otherwise suitably secured to the flange, through which water or other cooling liquid may 40 be circulated by the means about to be described.

45 Secured on the shaft 10, for rotation therewith, are a pair of semi-circular headers 18 and 19, which are preferably secured together by bolts or other suitable means, as may be seen in Figure 3. The header 18, through which the incoming cooling water passes, is connected, by means of a conduit 20, with the water jacket 17, and by means of a conduit 21 with the water jacket 17'. The header 19, through which the outgoing heated

water passes, is connected with the water jacket 17 through a conduit 22, and with the water jacket 17' by a conduit 23. The conduits 22 and 23 preferably communicate with the water jackets 17, 17' at points approximately diametrically opposed to the points at which the conduits 20 and 21 communicate with the water jackets.

The shaft 10 is provided with a longitudinal cylindrical recess 10' in which may be inserted a 10 unitary assembly comprising a semi-cylindrical inlet conduit 24, and a semi-cylindrical outlet conduit 25, the said conduits being separated by a layer of heat-insulating material 26 (see Figures 2 and 5). The conduits 24 and 25 are preferably welded together in assembled relation, thus forming, with the intervening layer of heat insulating material, a rigid unitary assembly which may be inserted bodily in the shaft. The inner end of the conduit 24 is provided with a port 27 20 which communicates, through a transverse passage 28 in the shaft 10, with the header 18. Similarly the conduit 25 is provided with a port 29 communicating with a transverse passage 30 which in turn communicates with the header 19.

25 The assembly comprising the conduits 24 and 25 is provided, at its outer end, with a sleeve 31, secured thereon and adapted to rotate therewith, the near or right hand end of the sleeve being adapted to fit into a corresponding recess in the 30 end of the shaft 10, being retained in place by means of a collar 32 secured to the end of the shaft by bolts 33 or other suitable means. Surrounding the sleeve 31, and journaled thereon so as to permit relative rotational movement of 35 the sleeve therein, there is a cylindrical member 34 which is provided with two annular chambers 35 and 36 separated by an inwardly projecting annular flange 37. Seated in the latter is a packing ring 38 which, in conjunction with the sleeve 40 31, serves to separate, in a water-tight manner, the annular chambers 35 and 36. Similarly, the annular chamber 36 is sealed off from the anti-friction bearing 39 by means of a packing ring 40, and the annular chamber 35 is sealed off 45 from the anti-friction bearing 41 by a packing ring 42. The anti-friction bearing 41 is also protected from atmospheric dirt by means of a cover plate 43 which closes the end of the cylindrical member 34.

50 The member 34 is provided with a port 44, into which is threaded a conduit 45 leading from a source of cooling water and communicating with the annular chamber 35, and thence, through a port 46, with the inlet conduit 24. Similarly, a conduit 47, threaded into the port 48, communicates with the annular chamber 36 and thence through a port 49 with the conduit 25, and is adapted to withdraw heated water therefrom and conduct it to a suitable disposal point.

60 From the foregoing, the manner in which the cooling water is circulated will be easily understood. Cooling water coming into the device through the conduit 45 passes into the annular chamber 35 and thence, through the port 46, into 65 the inlet conduit 24, through the transverse passage 28 and into the header 18. From the header 18 the cooling water passes through the conduits 20 and 21 to the water jackets 17 and 17' respectively, where it is circulated against the 70 flanges 14, 14' and serves to withdraw heat generated therein by the application of braking pressure. The heated water is withdrawn from the water jackets 17, 17' through the conduits 22 and 23, respectively, passing into the header 75 19, through the transverse passage 30, outlet con-

duit 25, annular chamber 36, and conduit 47, to the desired point of disposal. It will of course be apparent that all of the foregoing parts rotate, with the exception of the cylindrical member 34 and the conduits 45 and 47.

5 It is obvious that the conduits 24 and 25 need not be semi-cylindrical but may take any shape in which the two conduits have complementary adjacent surfaces. However, the semi-cylindrical form is particularly advantageous in that it enables the complete assembly to take a cylindrical form, facilitating its insertion in a cylindrical recess, which is most easily formed in the shaft. Obviously, the inlet and outlet conduits should always be separated by heat insulating material so that there will be a minimum transfer of heat from the outgoing heated water to the incoming cooling water.

Likewise the headers 18 and 19 might be other than semi-cylindrical in their outer configuration, but the semi-cylindrical form is preferable since it permits of a uniform angular distribution of the mass of the headers and their contents.

Having thus described the invention, what is claimed as new and desired to be secured by Letters Patent is:

1. In a device of the class described, a shaft, means supporting said shaft for rotation, a drum secured on said shaft, said drum having a braking surface, a liquid-tight jacket carried by said drum adjacent said braking surface, and means for circulating a cooling liquid through said jacket, said last named means comprising inlet and outlet conduits disposed longitudinally within said shaft, said conduits being separated by a layer of heat insulating material, means connecting said conduits and said jacket, means connecting said inlet conduit with a source of cooling liquid, and means connecting with said outlet conduit for conducting liquid therefrom. 40

2. A device according to claim 1, said inlet and outlet conduits being formed with complementary adjacent surfaces, said conduits being rigidly secured together, with said layer of heat insulating material disposed therebetween, to 45 form a unitary assembly.

3. A device according to claim 1, said inlet and outlet conduits being of semi-cylindrical form and being welded together, with said layer of heat insulating material disposed therebetween, to form a unitary assembly. 50

4. In a device of the class described, a shaft, means supporting said shaft for rotation, a drum secured on said shaft, said drum having a braking surface, a liquid-tight jacket carried by said drum adjacent said braking surface, and means for circulating a cooling liquid through said jacket, said last named means comprising inlet and outlet conduits disposed longitudinally within said shaft and projecting outwardly from one end thereof, said conduits being separated by a layer of heat insulating material, a sleeve surrounding said projecting ends of said conduits and secured to said shaft for rotation therewith, a member mounted on said sleeve and in which said sleeve is journaled for rotation relative thereto, said member having two internal annular chambers, means connecting said inlet conduit with one of said annular chambers, means connecting said annular chamber with a source of cooling liquid, and means connecting said outlet conduit with said second annular chamber, said second annular chamber having a port extending outwardly therefrom. 60 65 70 75 80

5. In a device of the class described, a shaft, 75

- means supporting said shaft for rotation, a drum secured on said shaft, said shaft having a plurality of braking surfaces, a liquid-tight jacket carried by said drum adjacent each of said braking surfaces, and means for circulating a cooling liquid through each of said jackets, said last named means comprising a pair of headers secured on said shaft for rotation therewith, conduits connecting each of said headers with each 5 of said jackets, an inlet conduit connecting with one of said headers, an outlet conduit connecting with said other header, said inlet and outlet conduits being disposed longitudinally within said shaft and separated by a layer of heat insulating material, means connecting said inlet conduit with a source of cooling water, and means connecting with said outlet conduit for conducting liquid therefrom.
6. A device according to claim 5, said inlet and 20 outlet conduits being formed with complementary adjacent surfaces, said conduits being rigidly secured together, with said layers of heat insulating material disposed therebetween, to form a unitary assembly.
- 25 7. A device according to claim 5, said inlet and outlet conduits being of semi-cylindrical form and being welded together, with said layer of heat insulating material disposed therebetween, to form a unitary assembly.

8. In a device of the class described, a shaft, means supporting said shaft for rotation, a drum secured on said shaft, said shaft having a plurality of braking surfaces, a liquid-tight jacket carried by said drum adjacent each of said braking surfaces, and means for circulating a cooling liquid through each of said jackets, said last named means comprising a pair of headers secured on said shaft for rotation therewith, conduits connecting each of said headers with each 5 of said jackets, an inlet conduit connecting with one of said headers, an outlet conduit connecting with said other header, said inlet and outlet conduits being disposed longitudinally within said shaft and projecting outwardly from one 10 end thereof, said conduits being separated by a layer of heat insulating material, a sleeve surrounding said projecting ends of said conduits and secured to said shaft for rotation therewith, a member mounted on said sleeve for rotation 20 relative thereto, said member having two internal annular chambers, means connecting said inlet conduit with one of said annular chambers, means connecting said annular chamber with a source of cooling liquid and means connecting 25 said outlet conduit with said second annular chamber, said second annular chamber having a port extending outwardly therefrom.

JOHN HART WILSON.
